[57] CLAIM

The ornamental design for a base for a telephone handset, as shown and described.

DESCRIPTION

FIG. 1 is a perspective view of a base for a telephone handset, showing our new design the telephone handset and cord having been shown by means of broken lines for illustrative purposes only;

FIG. 2 is a front plan view thereof;

FIG. 3 is a back plan view thereof;

FIG. 4 is a right side elevational view thereof;

FIG. 5 is a left side elevational thereof;

FIG. 6 is a top view thereof; and,

FIG. 7 is a bottom view thereof.

FIG. 1

FIG. 2

FIG. 3

FIG. 4

FIG. 5

FIG. 6

FIG. 7
